UNITED STATES PATENT OFFICE

LEE C. STEELE, OF SOUTH BEND, INDIANA

WINDOW SCREEN

Application filed July 7, 1928. Serial No. 291,010.

The invention relates to window screens, and has for its object to provide upper and lower overlapping screens disposed in a window frame and adapted for vertical movement therein.

A further object is to provide a window screen comprised of upper and lower overlapping screens both removably disposed in a window frame, and adapted for vertical movement therein, the upper screen being held in position by spring means carried by said window frame, said spring means also being adapted to hold the lower screen when in raised position.

15 A further object is to provide a window screen comprised of upper and lower slidable screens disposed in a window frame, said window frame having channeled portions formed to guide and retain the upper screen by contact with resilient gripping members, and the channeled portions being open on one side for a portion of their length, whereby both screens may be easily and quickly applied or removed from the window frame from 20 within the building.

With the above the other objects in view, the invention resides in the particular combination and arrangement of parts as hereininafter set forth, shown in the drawing, described and claimed, it being understood that changes in the precise embodiment of the invention may be made within the scope of what is claimed without departing from the spirit of the invention.

25 In the drawings:

Figure 1 is a view in elevation of the screen as installed in the window frame.

Figure 2 is a vertical sectional view taken on line 2-2 of Figure 1.

30 Figure 3 is a vertical sectional view taken on line 2-2 of Figure 1 showing the lower screen in raised position.

Figure 4 is a fragmentary view in elevation of the window frame showing the spring member.

35 Referring to the drawing, the numeral 1 designates a window frame of the conventional type, having stiles 2, upper rail 3 and sill 4. Carried by the window frame at the rear thereof are the frame guide members

5 which extend completely around the frame. Carried by the upper half of the stiles at the inner sides thereof are the guide members 6 which are preferably made of angle iron. The guide members 6 cooperate with the 55 frame guide members 5 and the stiles 2 to form a channel 7 at the upper part of the inner side of each stile.

Disposed in the window frame and in the channel 7 are an upper screen 8 and a lower 60 screen 9, which overlap at their meeting point. The screens are preferably formed with metal frames, but any suitable frame may be used. The upper screen 8 is disposed almost entirely within the channels 65 7 and is held in position by contact at their upper ends with the spring members 10, which are preferably leaf springs, but may be of any type suitable for the purpose. The spring members 10 are disposed in the channels 7 and are preferably secured to the opposite vertical frame guide members 5 at the upper ends thereof. The spring members 10 extend outwardly in natural position and almost touch the guide members 6. The upper 70 screen 8 is placed in the channels 7 in a position to touch the rail 3 of the window frame, and when in that position the springs 10 tend to push the upper end of the screen 8 outwardly against the guide members 6, and in that manner frictionally hold it in its proper position.

75 The lower screen 9 rests upon the sill 4 of the window frame, and has its upper end slightly extending into the channels 7 and 80 in a position overlapping the lower end of the upper screen 8. The lower end of the lower screen 9 is disposed between the lower horizontal frame guide member 5 and the stops 11, which are carried by the sill 4 of the window frame, and which prevent the lower end of the screen 9 from shifting forwardly in the window frame and from falling out of the frame. The frame of the lower screen 9 also carries a handle member 12 85 by which the screen may be raised and lowered.

90 It will be seen from the above that in normal closed position the upper screen 8 is disposed in the channels 7 and is there held 100

- by the springs 10 which press the screen against the guide member 6; and the lower screen 9 rests on the sill 4 between the frame guide members 5 and the stops 11, and has its upper end overlapping the lower end of the screen 8 in the channels 7. When it is desired to raise the lower screen it may be done by pushing it up in the channels 7 and when it is so raised it will remain in the position in which it is placed. In raising the lower screen the springs 10 are further depressed by the screen 8 against which the raised lower screen 9 pushes in being raised, as shown in Figure 3, and consequently the spring pushes outwardly against the screen 8 and through it against the screen 9 which is consequently firmly wedged and held between the screen 8 and the guide members 6, and may thus be held in any position to which it may be raised.
- It will also be seen that the screens may easily be removed from and installed in the window frame. The lower screen 9 may be removed by lifting it above the stops 11, pushing its lower end outwardly clear of the sill and then pulling its upper end down free from the channels 7. The upper screen may then be readily removed by pulling it down out of engagement with the springs 10 and then clear of the channels 7.
- It will thus be obvious from the foregoing that the improvement contemplates an exceedingly simple structure, whence the screens may be easily and quickly installed or removed from within the building, the advantages of which are apparent, especially with respect to screened windows on upper floors.
- The invention having been set forth, what is claimed as new and useful is:
1. In a window screen device, screen receiving members, upper and lower screens slidably disposed in said members, and means carried by and cooperating with said screen receiving members to secure the upper screen in operative position, and to hold the lower screen to place when in a raised position.
  2. In a window screen device, U-shaped guide members, upper and lower screens slidably disposed in said guide members and adapted for vertical movement therein, and a spring member carried by each guide member at the upper end thereof, said spring members forming means for holding the upper screen in operative position and for holding said lower screen in raised position.
  3. In a window screen device, U-shaped guide members, upper and lower screens slidably disposed in said guide members and adapted for vertical movement therein, and a spring member carried by each guide member at the upper end thereof, said spring members forming means for holding the upper screen in operative position and for holding said lower screen in raised position,

one flange of each guide terminating short of the bottom of said guide, whereby the screens may be removed from said guides.

In testimony whereof I affix my signature.

LEE C. STEELE.
